UNITED STATES PATENT OFFICE.

VITO ORAZIO RAIMONDI, OF CHICAGO, ILLINOIS.

DESIGN FOR AN EDIBLE CONTAINER.

Application filed September 7, 1928. Serial No. 28,065. Term of patent 3½ years.

To all whom it may concern:

Be it known that I, VITO ORAZIO RAIMONDI, a citizen of the United States, residing in Chicago, in the county of Cook and State of Illinois, have invented a new, original, and ornamental Design for an Edible Container, of which the following is a specification, reference being had to the accompanying drawing, forming a part thereof.

In the drawing, Fig. 1 is a plan view and Fig. 2 is an elevational view of the edible container embodying my design.

I claim:

The ornamental design for an edible container as shown.

VITO ORAZIO RAIMONDI.
